OWEN AUBREY ELIAS,

By: O. A. Elias & Company
atty: John Smith

UNITED STATES PATENT OFFICE.

OWEN AUBREY ELIAS, OF LONDON, ENGLAND.

PREPARATION OF AERATED BEVERAGES.

Application filed March 20, 1923. Serial No. 626,436.

To all whom it may concern:

Be it known that I, OWEN AUBREY ELIAS, a subject of the King of England, residing at New Cross, in the city of London, in the 5 Kingdom of England, have invented certain new and useful Improvements in the Preparation of Aerated Beverages, of which the following is a specification.

This invention relates to a treatment of 10 liquids with gases and more especially with various inert or rare gases in such a manner as will ensure the absorption and retention of the gas or gases to an equivalent degree and sometimes even to a higher degree than 15 is found in the natural waters or mineral springs.

According to my invention, I introduce in a suitable liquid an inert gas or gases of the argon series singly or in combination, by 20 pressure, injection or displacement, proportionate to or in excess of the quantity or quantities contained in a natural mineral spring. For this purpose I provide a closed vessel fitted with an ordinary agitating or 25 mixing device such as is used for carbonating water, and containing the liquid to be treated.

During the churning operation I introduce a mixture of the inert gas or gases 30 gradually under pressure with CO₂ from the container.

For the aforesaid purpose, I may use helium or gases of the argon series which, under ordinary conditions are sparingly 35 soluble, but will be absorbed by the liquid to a greater degree when thoroughly mixed, agitated or churned under pressure with the liquid in a closed vessel in the presence of CO₂. The pressure and CO₂ thus serve to aid 40 the better absorption and concentration of the gas or gases during the churning operation and retain them for a reasonably long period, whilst the argon group of gases increase the therapeutic value of aerated 45 liquids which comprise in a general way mineral or aerated waters, cordials, and similar beverages.

In modern aerating machines the mixing or churning process is replaced by a saturating process often called "reduced pressure" principle and this is equally suitable for use 50 with my invention.

The accompanying drawing illustrates, by way of example, a suitable device for promoting an effective admixture of the said

rare gas or gases with CO₂, which admixture is most difficult to obtain by ordinary means and unless very intimately mixed the helium and carbonic acid will separate.

For my purpose, according to repeated 60 experiments, I may adopt a spraying and mixing tube, which consists in a small and preferably taper-ended pipe A for the rare gas. The tube A is held tight in a disc B of a surrounding tube C having a side supply tube D for the carbon dioxide. The issue from the pipe A of the rare gas, or gases, is located at about the place where the carbon dioxide is admitted and is so arranged as to lead to the atomizing or diffusion of the gases in the tube C. Thus C 70 constitutes a practical diffusion chamber which may, or not, have a restricted neck portion C¹. Fixed in the neck C¹ or in the end of the tube C is a tube E containing a nozzle F having a comparative wide inlet passage G with rounded edges, or it may be a tapering passage, said passage leading into narrow diverging channels H the issue portions of which are curved towards each other, that is to say towards the centre of the nozzle. Streamlets of gases from the diffusion chamber are thus directed towards each other so as to produce whirls which induce the gases to mix intimately before 80 passing to a gas-holder, bell or other receptacle for injection into the mineral water or other liquid for human use which injection may be effected in any well known manner.

I claim:

1. An aerated liquid having stable therapeutic properties prepared by intimately mixing helium with carbonic acid, and introducing same into the liquid in known 90 manner.

2. The treatment of liquids with helium by introducing same with carbonic acid into a diffusing chamber, through an intimately admixing device and thence into a gas holder whence the gases are extracted and introduced into the liquid in known manner.

3. The treatment of liquids with helium by introducing same with carbonic acid and other inert gases into a diffusing chamber, through a spraying and mixing tube and thence into a gas holder whence the gases are extracted and introduced into the liquid in known manner.

OWEN AUBREY ELIAS.
